Edwin S. Brock
ATTORNEY

UNITED STATES PATENT OFFICE

SIDNEY U. BARR, OF MONTCLAIR, NEW JERSEY

VENTILATOR.

Application filed March 8, 1929. Serial No. 345,314.

This invention relates to ventilators for windows and particularly to that type of ventilators wherein the sheet of glass or of other suitable material is disposed, as an air deflector, in angular relation to a window and mounted on the window sill between window frame sides.

The object of the invention is to provide a readily adjustable device of the class indicated and especially useful in metal window frame 10 construction.

Referring to the accompanying drawings forming a part hereof and illustrating the invention:

Fig. 1 is a front elevation with the intermediate part of the ventilator and window broken away for economy of space;

Fig. 2 is a cross-sectional view taken on line 2—2 of Fig. 1, looking in the direction of the arrows. In this view the wind shield is shown in full lines close to the window and the broken lines indicate it in the fully opened position;

Fig. 3 is a sectional plan view taken on line 25 3—3 of Fig. 2, looking in the direction of the arrows;

Fig. 4 is a detail sectional view on a larger scale, taken on the line 4—4 of Fig. 2. In this view only the frame is illustrated and the intermediate part thereof is broken away; and

Fig. 5 is a detail sectional view on a larger scale of the lower part of the ventilator.

Referring to the drawings, the reference numeral 6 indicates a sliding sash and window pane. The window frame comprises the sill portion 7 and frame sides 8.

Secured by screws 9 to the side portions of the window frame are V-shaped air and wind deflector plates 10 having flanges 11 on their inward or forward edges remote from the window. The upper edges 12 of these V-shaped plates are curved and flanges 11 extend upwardly and inwardly.

Channel members 13 are pivoted at 14 to the V-shaped plates 10. These channel members fit snugly against the plates 10 and carry the deflector 15. One of each of the legs of the channel members is bent at right angles, as

indicated at 16, and acts as a bottom support for the ventilator 15. A strip of rubber 17, or other suitable material, is secured to the deflector between its lower edge and the sill 7 so as to prevent any draught or air entering the room, except that which is deflected upward by the deflector plate.

The upper parts of the members 13 extend above the frames 10 and have secured thereto by screws 18, or other suitable means, 60 strong flat spring 19. The free ends 20 of these springs, as particularly shown in Fig. 4, bear against the outer sides of the plates 10. The curved edge 12 of the plates 10 are in an arc, the center of which would be struck from the pivot pins 14. The flanges 11 prevent the channel members 13 from being moved off the plates 10.

It will be apparent from the foregoing description and an inspection of the drawings 70 that when the device is assembled one may easily grasp the deflector, or use the two upwardly-extending ends of the channel members 13 for handles, and move the deflector 15 from the full open position indicated in 75 broken lines in Fig. 2 to a substantially vertical position, thus controlling the amount of fresh air to be admitted and the direction in which it will be deflected. The springs 19 form a simple and efficient means for holding 80 the ventilator in its desired position.

The pivotal connection of the channel bar members which form a frame for the deflector 15 is between the deflector-holding frame and the side plates, preferably of metal, which 85 are secured to the window frame sides. The preferably compressible strip 17 serves to exclude a draught between the window sill and the under edge of the deflector.

What I claim is:

As a new article of manufacture, an air-deflecting, window ventilator including a rockable, air-deflecting plate; a frame therefor comprising channeled members in which the plate is loosely mounted and slidable into and out of the frame; and rigid end plates to each of which the plate-holding frame is pivoted adjacent the under end of an end plate; means for holding said frame in adjustable 95 position, the end plates being adapted for con- 100

nection with the window frame sides; and a strip of compressible material along the under edge of the frame structure adapted to engage a window sill and be compressed thereagainst when in use; the upper edges of the rigid end plates being severally arced from its upper, outer corner portion, inwardly, from its pivoted connection with the plate holding frame as a center, the channeled members of the plate holding frame including side members which project above the upper edges of the end frames; the outer surfaces of the projecting channeled members being flat and the inward surfaces of the end frames being flat and the flat outer surfaces of the projecting channeled members each being in sliding contact with a flat inward surface of an end frame; the end of a channeled member projecting above the upper edge of an end frame having secured to it a downwardly extending leaf spring, the under free end of which is in engagement slidingly with the outward surface of an end frame.

Signed at Brooklyn, in the county of Kings and State of New York, this 5th day of February, 1929.

SIDNEY U. BARR.
